his Attorney.

UNITED STATES PATENT OFFICE

ALBERT H. WALDE, OF ROXBOROUGH, PENNSYLVANIA

BATTERY TERMINAL

Application filed August 28, 1928. Serial No. 302,575.

My invention relates broadly to electrical connectors and more particularly to an electrical connector for storage battery terminals.

5 One of the objects of my invention is to provide an improved construction of connector for storage battery terminals by which connection may be made with a storage battery terminal without the necessity of applying solder at the point of junction.

Another object of my invention is to provide a construction of storage battery terminal having means for establishing a quick detachable connection to the terminal posts 15 of a storage battery where means are provided for substantially enclosing the end of the insulated covering on the flexible conductor which leads to the terminal for preventing an attack of acid upon the conductor 20 at its point of connection to the battery terminal.

Still another object of my invention is to provide a solderless connector for a storage battery terminal comprising a pair of co- 25 operating parts threaded one into the other where provision is made for independently gripping both parts of the terminal while telescopically advancing the parts one into the other to a position where the end of a conductor may be rigidly gripped within the terminal for establishing good electrical connection, while protecting the conductor 30 against the attack of acid.

My improved connection will be more fully understood from the specification herein- 35 after following by reference to the accompanying drawings, in which:

Figure 1 is a side elevation of the connector of my invention; Fig. 2 is a cross-sectional view taken through the connector of my invention and showing a flexible conductor extending to the terminal and rigidly secured in position therein; Fig. 3 is a side view of one part of the storage battery terminal; Fig. 4 is an end view of the part of the storage battery terminal shown in Fig. 3; Fig. 5 is an end view of the conical shaped screw threaded insert employed in connection with the part of the storage battery terminal 50 shown in Figs 3 and 4; Fig. 6 is a cross-

sectional view taken through the insert illustrated in Fig. 5; and Fig. 7 is an end view of the insert.

The battery terminal of my invention is so constructed that the parts may be readily assembled or removed with respect to the cable which connects to the battery. By providing the connector of my invention with a plurality of flattened surfaces adjacent the periphery at the end of thereof, a tool such as a wrench may be used to grip the terminal and rotate the terminal with respect to the screw threaded insert until the insert reaches a position within the connector. The insert for the storage battery is provided with a 55 socket opening in the end thereof which provides a protection for the insulation of the conductor and establishes a selected connection between the entrance of the insert and the conductor to prevent the leakage of acid 60 into the connector and the corrosion thereof within the connector. The insert is provided with slotted screw threaded portions which tend to move inwardly to grip the end of the conductor as the insert is screwed 65 into the connector. The slots in the insert terminate short of the end of the insert and are fully governed by the connector when the insert is screwed to a final position within the connector, thereby preventing the leakage 70 of acid into the connector and guarding the electrical connection thus established 75 from corrosion.

My invention will be more clearly understood by detailed reference to the drawings, 85 wherein reference character 1 designates a strap member which encircles the post of a storage battery. The strap member 1 terminates in integral extensions 2 and 3 through which bolt member 4 passes. The bolt member 4 is provided with a head 5 and is screw threaded to receive the adjusting nut 6 by which the strap 1 is secured to the binding post of the storage battery. The connector includes the frusto-conical shaped barrel portion 3 which is integrally screw threaded as represented at 8. The outer extremity of the frusto-conical portion 3 is provided with a plurality of flattened surfaces 7 to enable the connector to be readily gripped by a wrench 90 95 100

or tool in order that it may be rotated with respect to the insert represented in Fig. 6 until the insert is moved to a position within the frusto-conical portion 3. The insert is provided with a tapered barrel portion screw threaded on the exterior thereof, as represented at 9, and at the extremity thereof a plurality of flattened surfaces 11 are provided by which the insert may be gripped while 10 the barrel portion 3 is being rotated to move the insert to a position within the connector, the screw threads 9 engaging the screw threads 8. The insert is provided with a socket portion 12 at the end thereof which 15 terminates in an angular wall 14 which connects to the interior bore of the insert. Slots 10 are cut in the screw threaded portion of the bore to enable the parts of the insert to be moved under the wedge action brought about 20 by the movement of the insert into the connector to a position where the end of cable 16 is gripped and electrical connection established therewith. It will be observed that the slots 10 extend slightly over one-half of the 25 length of the insert so that when the insert is screwed to a limiting position within the connector, the slots are entirely closed by the connector so that no sections of the metallic cable remain exposed which can be attacked by 30 acid.

The socket 12 forms an enclosure for the insulation 15 of a flexible cable 16, the cable extending into the insert and having the end portion thereof gripped by the insert, while 35 the end of the insulation is protected against the attack of acid. The bored cable is initially scraped and cleaned and forced into the bore of the insert to insure a good contact between the connector and the cable.

40 The terminal connector of my invention has been found to be extremely practical in its construction, and while I have illustrated the terminal in one of its preferred embodiments, I desire that it be understood that modifications may be made and that no limitations 45 upon my invention are intended other than are imposed by the scope of the appended claim.

What I claim as new and desire to secure 50 by Letters Patent of the United States is as follows:

A storage battery terminal comprising a casting having a portion thereof forming a connector for a storage battery post, a frusto- 55 to-conical portion on said casting having internal screw threads throughout the length thereof, and a frusto-conical insert enclosing the end of a cable, screw threads on said insert extending to one end thereof for engaging 60 the internal screw threads in the frusto-conical portion of said casting, said insert having a slotted portion at one end and a housing portion at the other end, the slotted portion being spaced from the housing portion, 65 and said housing portion extending into the

frusto-conical portion of said casting when said insert is screwed to a limiting position therein for preventing leakage of acid into said connector, said housing portion being adapted to receive the insulated portion of the cable.

In testimony whereof I affix my signature.
ALBERT H. WALDE.
